UNITED STATES PATENT OFFICE.

ALBERT H. PEDRICK, OF SPRINGFIELD, OHIO.

PAVEMENT-CUTTING MACHINE.

1,271,757.

Specification of Letters Patent.

Patented July 9, 1918.

Application filed January 18, 1916. Serial No. 72,764.

To all whom it may concern:

Be it known that I, ALBERT H. PEDRICK, a citizen of the United States, residing at Springfield, Clark county, State of Ohio, 5 have invented certain new and useful Improvements in Pavement-Cutting Machines, of which the following is a specification.

This invention relates to machines for cutting asphalt pavements or pavements of 10 like composition, particularly to machines adapted to cut a groove or channel through an asphalt or similar surface in the partial or whole destruction of a street pavement for repair or reconstruction purposes.

15 The object of this invention is to provide a machine which will cut a channel through the surface of the pavement quickly and with a minimum of power expenditure and of supervision by attendants and which may 20 be quickly and easily transported from place to place in the operation of street repair or reconstruction gangs.

In the accompanying drawings in which one form of my invention is shown in detail, 25 Figure 1 is a top plan view;

Fig. 2 is a side elevation;

Fig. 2^a is a perspective view of the propelling device for the machine;

Fig. 3 is a front end view of the machine 30 with part of the mechanism in section;

Fig. 4 is a detail illustrating the cutter tooth construction;

Fig. 5 is a section on the line 5—5 of Fig. 4.

35 Fig. 6 is a side view of another embodiment of the invention.

Referring to Figs. 1, 2 and 3 of the drawings, 10, 10 represent a pair of road wheels, supporting a shaft or axle 11. A heavy 40 frame 12 is journaled at one end on the shaft 11 and extends forwardly therefrom after the manner of a wagon frame. This heavy frame has downwardly extending arms 13 and 14 at its forward end which carry a 45 shaft 15, this shaft being held from rotation by pins 16 and 17 which pass through the arms 13 and 14 and the shaft. Keyed to this stationary shaft 15 near the middle thereof is a bracket or spider 18 on which are journaled two pinions 19 and 20. Journaled on the opposite sides of the bracket 18 are two cutter wheels 21 and 22, which are provided on their inner sides with gear teeth adapted to engage the pinions 19 and 20. The cutter 55 wheels are provided on their peripheries with series of cutter teeth 23 attached there-

to by bolts 24, these teeth projecting a distance beyond the periphery of the cutter wheels to act as saw teeth in the cutting of the pavement. Bolted to a flange 25 rigid with the cutter wheel 21 or otherwise suitably rigidly attached to this cutter wheel is a worm wheel 26 which is caused to rotate in the cutting operation of the machine, thereby rotating the cutter wheel 21 in the same direction on the shaft 15. The cutter wheel 21 imparts its rotary motion by means of its internal teeth to the pinions 19 and 20 which rotate the cutter wheel 22 in a direction opposite to the direction of rotation of the cutter wheel 21. The teeth of the cutter wheels being close together cut the material which they engage in a manner similar to that in which a pair of scissors operates. The movement of the cutter wheels in opposite directions to cut the asphalt pavement prevents the cutting action from imparting a longitudinal movement to the machine as a whole, and has the added advantage that the teeth in passing one another knock off from each other any particles or lumps of asphalt or other material which may be clinging to them, thus keeping the cutting portions of the teeth free from matter which might impair their cutting action. Meshing 85 with the worm wheel 26 is a worm 27, which is mounted on a shaft 28 journaled in the frame 12 of the machine at the ends thereof. At one end of the shaft 28 is a bevel gear 29 which meshes with a bevel gear 30 rigidly 90 attached to a sleeve 31 journaled on the axle 11, this sleeve 31 being rigidly attached by any suitable means to a pulley 32 also journaled on the shaft 11. To take up the end thrusts in the worm shaft roller, thrust 95 bearings 33 and 34 are placed at the end of the worm shaft adjacent the cutter wheels. The pulley 32 is driven by a belt 35 from a motor 36 which may be of any suitable type such as an electric or internal combustion. The motor 36 is mounted on a platform 37, suspended at one end from the axle 11 and extending forwardly under the frame 12 to a point adjacent the cutter wheels where it is supported from the ground by a 105 swivel wheel 38, said platform being always in a horizontal position. Extending directly upward from the end of the frame 37 above the swivel wheel 38 is a threaded rod 39 which extends above the frame 12 of the 110 machine and passes through a bracket 40, which is rigidly attached to the frame 12.

by means of bolts 41 and 42. Immediately below the bracket 40 and mounted on the threaded rod 39 is an interiorly threaded hand wheel 43 adapted to abut against the 5 lower part of the bracket 40 and to raise and lower, through its rotation about the rod 39, the heavy frame 12 of the machine and the cutter wheels.

In the operation of cutting, the hand 10 wheel is so adjusted that the frame and cutter wheels are lowered until the teeth on the cutter wheels penetrate the pavement the necessary distance. When, however, it is desired to move the machine, the hand wheel 15 is turned and the whole forward end of the machine, including the cutter wheels, is raised until the teeth no longer engage the pavement. When in this position the machine may be drawn from place to place, its 20 entire weight resting upon the road wheels 10 and the swivel wheel 38.

Any suitable means may be employed for slowly advancing this form of the machine in operation. I have shown a propelling 25 device mounted on the crank shaft or motor driving shaft 60 and extending downward through an opening 61 in the platform of the frame 37, on which the motor 36 is mounted. The propelling mechanism has a frame 30 62 which has a yoke 63 at the upper end provided with bearings fitting on opposite sides of a worm 64 on the shaft 60, the shaft 60 being rotatably mounted in opposite sides of the frame 37. The frame 62 is arranged 35 so that it may oscillate on the shaft 60 and at its lower end it has another yoke 65 provided with suitable downwardly extending arms 66, forming bearings engaging the opposite ends of a shaft 67, carrying the spiked 40 wheel 68 and the worm wheel 69, the worm wheel and spiked wheel being rigidly secured together so as to rotate as one. The yokes 63 and 65 are provided on their upper sides with suitable bearings to support 45 a shaft 70 which at its upper end carries a worm wheel 71, meshing with the worm 64 on the drive shaft 60. The shaft 70 carries a worm 72 at its lower end which meshes 50 with the worm wheel 69 connected to the spiked wheel 68. The spiked wheel engages the concrete at the bottom of the groove 55 cut by the cutters 23 and is geared to turn slowly at about the speed necessary to cut the asphalt. As it requires little power to move the machine forward, a simple lever or handle 73 is sufficient to raise the propelling frame, should it be necessary to back up the cutting machine in order to go over some place a second time. The handle lever 73 is 60 one arm of an elbow lever pivoted at 74 on a bar 75 which extends across the upper side of the frame 37. The lower arm 76 of the elbow is connected by a link 77 to the frame 62. A notched segment 78 is mounted on the bar 75 and a locking device 79 on the han-

dle serves to lock the elbow lever and the frame carried thereby in either raised, lowered or intermediate position.

In the form of my cutting device shown in Fig. 6 the shaft 11' instead of being mounted on a pair of road wheels is supported on brackets 50 which are secured to the rear platform of a traction engine A by means of bolts 51. The shaft 11' is preferably mounted in bearings 52 on the brackets having the upper halves 53 of the bearings removably secured to the brackets by bolts 54, 54. The cutter may be thus quickly detached from the traction engine by unfastening bolts 54 and lifting the shaft 11' from the bearings. The operation of the cutting apparatus is the same in this modification as in the form previously described but the power for rotating the cutters is in this case derived from the traction engine A instead of from a separate motor on the cutter. The pulley 32' mounted on the shaft 11' is connected with a pulley 55 driven by the motor of the traction engine by a belt 56.

By attaching my cutting device to a traction engine a means for drawing the cutter along is provided as well as a source of steady power for rotating the cutter wheels. Only one man is needed in the operation of both devices and the traction engine is adapted to move the cutter rapidly from place to place to operate on different pieces of work.

It is obvious that many changes may be made in the details of construction and arrangement of my machine and hence I do not wish to limit myself to the exact form illustrated and described.

Having thus described my invention, what is claimed and desired to be secured by Letters Patent is:

1. In a machine for cutting channels in pavement, the combination with supporting wheels, of a frame pivotally supported on a transverse axis, a shaft mounted in the forward end of the frame, two cutter wheels arranged close together and operating in parallel planes at right angles to the shaft, means for turning the cutter wheels in opposite directions simultaneously, and means for feeding the machine to cut a groove in the pavement, said feeding means comprising a toothed wheel arranged to travel in the channel formed by the cutters and means for turning said wheel.

2. In a machine for cutting channels in pavement, the combination with suitable supporting wheels, of a cutter frame, a fixed shaft mounted in the cutter frame, a spider fixed on said shaft, pinions mounted on radial bearings on the spider, cutter wheels on opposite sides of said spider provided with gear teeth engaging said pinions, the peripheries of said cutter wheels lying close to

gether and being provided with cutters adapted to form a narrow channel in the pavement, and suitable gearing for turning one of said cutter wheels, motion in the opposite direction being imparted to the other cutter wheel through said pinions.

3. In a machine for cutting channels in pavement, the combination with suitable supporting wheels, of a cutter frame, a fixed shaft mounted in the cutter frame, a spider fixed on said shaft, pinions mounted on radial bearings on the spider, cutter wheels on opposite sides of said spider provided with gear teeth engaging said pinions, the peripheries of said cutter wheels lying close together and being provided with cutters adapted to form a narrow channel in the pavement, a worm and worm wheel for imparting a slow rotary movement to one of said cutter wheels, the other cutter wheel being driven in the opposite direction through the intermediate pinions, and means for imparting a slow forward movement to said machine.
- 25 4. In a machine for cutting channels in pavement, the combination with suitable

supporting wheels, of a cutter frame, a fixed shaft mounted in the cutter frame, a spider fixed on said shaft, pinions mounted on radial bearings on the spider, cutter wheels on opposite sides of said spider provided with gear teeth engaging said pinions, the peripheries of said cutter wheels lying close together and being provided with cutters adapted to form a narrow channel in the pavement, a worm and worm wheel for imparting a slow rotary movement to one of said cutter wheels, the other cutter wheel being driven in the opposite direction through the intermediate pinions, and means for imparting a slow forward movement to said machine.

5. In a machine for cutting channels in pavement, the combination with supporting wheels, a frame, groove cutting means carried by said frame, and means for feeding the machine to cut a groove in the pavement, said feeding means comprising a toothed wheel arranged to travel in the channel formed by the cutting means.

In testimony whereof I affix my signature.
ALBERT H. PEDRICK.
